UNITED STATES PATENT OFFICE

MARCUS A. ACHESON AND JAMES L. ZEHNER, OF SCHENECTADY, NEW YORK, ASSIGNEES
TO GENERAL ELECTRIC COMPANY, A CORPORATION OF NEW YORK

ELECTRON DISCHARGE APPARATUS

Application filed September 4, 1928. Serial No. 303,698.

The present invention relates to electron discharge apparatus and more particularly to devices in which the current is carried principally by electrons but which contain a relatively small amount of ionizing vapor for reducing space charge. In thermionic devices that employ, inter alia, an electron-emitting cathode, an anode and mercury or other form of ion-producing vapor for the purpose stated, the mercury has heretofore been introduced into the envelope as a liquid which collects as a small pool or globule at the bottom of the container. The reduction of space charge by means of an ion-producing vapor with which the subject-matter of the present invention is concerned in a broad sense, is to be sharply distinguished from the case where these vapors are employed as the principal electrical conducting media between electrodes, as in mercury arc rectifiers. In electronic discharge devices in which the current is carried principally by electrons derived from a heated body, usually a filament, the magnitude of the particle stream, hence, the current-carrying capacity of the device, is limited strictly to the electron-emitting power of the filament. The effect of space charge in such devices is to produce a curtailment of the particle stream, so strong under certain conditions as compared with the limited number of electrons present, as substantially to prevent further current flow. The introduction of mercury or other easily ionized vapor into the envelope is simply for the purpose of removing this effect so as to allow the electrons emanated by the filament, to flow more freely across the evacuated space. On the other hand, mercury arc devices do not employ electron emitters of the heated solid body type and the stream is not of limited magnitude inasmuch as the electrons are formed, in a cumulative manner and in endless number from the mercury vapor by collision between the vapor molecules and the electrons initially generated and propelled at an ionizing velocity through the vapor. Space charge thus presents no problem in devices of this sort which employ large amounts of ionizable vapor or which other-

wise provide for the generation of an abundance of space current carriers.

It has been noted in the case of space charge phenomena that when the vapor source is in the condensed form, liquid or solid, an appreciable time period normally elapses from the moment the voltage initially is applied to the electrodes until the vapor is generated and assumes a constant pressure. Under these conditions, it has been found that even after continued operation, the pressure still tends to fluctuate quite widely with relatively small changes of ambient temperature and becomes exceedingly difficult to regulate. The vapor pressure is a critical but important factor in a tube of this type and must be confined to rather narrow limits because too high a pressure causes arc-back or reverse current flow; on the other hand, when the pressure is too low, the voltage drop increases, producing a relatively high ion velocity which causes disintegration of the cathode material and other deleterious effects. Moreover, during the transportation and operation of a tube of this sort, extreme care must be exercised to prevent the mercury or other liquid material from splashing around within the envelope thereby giving trouble from short circuits.

We have discovered in accordance with our invention, that if the mercury or other space-charge-reducing body be spread or distributed over the surface or surfaces of one or more conveniently arranged elements within the tube, ordinarily the anode, which may be adapted to respond accurately to temperature control the derivation of the vapor and the facility with which the pressure thereafter is maintained, are considerably enhanced. In view of the fact that in the preferred embodiment there is no vapor-producing substance in liquid form present in the envelope, it is evident that the improved tube may be operated or transported in any position without subsequent danger of electrical failure.

Among the objects of the present invention are: to provide an electron discharge device in which the pressure of the space-charge-reducing vapor is quickly attained

and is accurately controllable within relatively narrow limits; to provide a tube in which the condensed vapor takes on the form of a solid, rather than liquid, and in general, 5 to improve the manufacture, construction and mode of operation of electrical translators of this character.

The drawing shows the application of our invention to a two-electrode rectifier comprising an elongated container which is highly evacuated prior to the introduction of the vapor-producing substance, preferably mercury, and in which numeral 1 designates a cylindrical anode closed at the bottom but 10 open at the top and made of a metal, such as copper, which readily forms an amalgam. The anode material may also consist of solid silver, silver-plate, copper-plate or any metal upon which can be formed a desirable coat, 15 condensate, amalgam or an alloyed surface with the group of materials referred to hereinafter as representative of the substances of which mercury is typical and from which the space-charge-reducing vapor may be derived. The anode is exteriorly arranged to facilitate cooling thereby to maintain the 20 temperature and pressure of the vapor either by an air blast or water contained in a jacket or other suitable fluid having a circulation, heat radiation or heat conservation which 25 may be regulated closely to control the anode temperature. The container is completed by a cylindrical top portion 2 ordinarily of Pyrex glass and having the lower end sealed to 30 the anode. For effectuating a thorough seal between the glass and metal surfaces, the upper end of the anode cylinder is flared outwardly and the material tapered down to a relatively sharp edge which is encased, by 35 fusing, into the lower end portion of the glass envelope drawn down to the same angle to coincide with the flared portion of the anode in the well-understood manner. For 40 a source of electrons, there is provided a member 3 of any suitable design, for example, filamentary; this member also serves as a cathode. Two V-shaped strands are connected in series, to form the cathode structure, the latter being conveniently supported 45 from a three-rod framework 4 of which the two outer rods serve as leading-in conductors. In order to protect the anode seal from 50 excessive heat radiated by the electron source and other parts and from deleterious electrostatic effects, there is provided a metallic cone-shaped shield 5 having a rolled or turned-in upper edge. The shield is centrally aligned of the envelope and held within the anode by friction or indentation. The 55 anode conductor conveniently may be taken from the temperature-controlling-fluid jacket. It is well-known that the maximum current obtainable in a tube of this character without the use of an ionizing vapor is limited by space charge, i. e., the electron-imped-

ing action produced by the negative charge or charges in the space between the electrodes by reason of the electrons therein. It is also well-understood that this current-limiting effect may be reduced by the addition of a small quantity of vapor, such as mercury, from which sufficient vapor may be derived to neutralize the restrictive negative charges referred to hereinbefore. When introduced 70 into the envelope in the manner employed by prior investigators for the purpose stated, the mercury ordinarily collects as a small condensed globule or pool at the bottom of the container. Under operating conditions, the derivation of the desired amount of vapor 75 from the globule is comparatively slow due to the small heat absorbing surface involved and even after sufficient vapor is produced, its pressure may vacillate materially under 80 relatively small changes of temperature because the source of heat which maintains the pressure is more or less localized. The slow 85 formation of the vapor and the non-uniform character of its pressure under the conditions stated, produce undesirable effects from the standpoint of space charge phenomena in all 90 forms of electron discharge devices but particularly so, in high-power, high-voltage apparatus. Moreover, when the mercury is admitted directly to the envelope in its condensed form, there is also the possibility of 95 including impurities which render the characteristics of the tube non-uniform.

In accordance with the present invention, we propose to condition and position the mercury or other condensate within the tube in such a manner that its effective heat absorption area is considerably greater than that of a globule of the same mercury content, thereby facilitating the production of 100 ion-producing vapor, also such that a heat radiating surface is provided sufficiently 105 large to maintain the vapor at relatively constant predetermined pressure. As additional 110 features, we introduce the mercury into the active region of the electrodes in a manner which will insure an extremely pure state of 115 the material and which will result in its being present only in a non-liquid form. The member from which the ion-producing vapor 120 is derived preferably takes the form of an amalgamated or an alloyed surface formed on the interior surface of the anode or on any other member within the device, the 125 temperature of which readily may be controlled and accurately maintained. This surface is obtained preferably by a distillation process and for this purpose there is provided a bent side arm 6 projecting from the glass envelope and terminating in a relatively large enclosed receptacle or compartment 7. Within the receptacle, there is a cylindrical flange member 8 of approximately 130 the same diameter as the glass arm and also a sharp ridge extending along the bottom 135

surface, the purpose of each of which will be explained hereinafter. In manufacture, the flange member preferably consists of an extension of the side arm and is formed by cutting an aperture in the top side of the receptacle 7 of a size corresponding to the external diameter of the side tube, then sliding the receptacle 7 over the tube a distance sufficient to form the flange, and fusing together the receptacle and the tube after the mercury or other vapor-producing substance has been introduced. While the mercury may be conducted directly to the receptacle 7 as a liquid, for example, by running it through the tube 6 before the latter is affixed to the envelope 2, we prefer to introduce the material in the form of a closed glass capsule 9 which may be held in an upright position by the flange 8, while the member 7 is being sealed to the side arm. The capsule prior to its insertion into the receptacle 7 is filled with mercury by a distillation process to ensure pure material. After being placed in the position shown and the side tube sealed to the envelope 2 which may be thoroughly evacuated in the well-understood manner, the entire envelope structure is given one or two shakes of sufficient intensity to cause the capsule to strike against the sharp ridge in the bottom of the receptacle and allow the mercury to escape. The mercury released in this manner is then heated either by the operating currents of the device or more quickly, if desired, by an external source of heat whereby the vapor distils through the tube 6 into the main envelope. In any case, the distillation process should not be carried out too rapidly as this tends to form an incomplete amalgamation, indeed, if there is available sufficient time, the heat derived by reason of ambient room temperature is particularly effective in forming a uniform coat or alloy. The vapor thus procured condenses and amalgamates with the interior surface of the anode which is maintained at the proper temperature for this purpose by the circulatory cooling fluid in case the tube is operating, whereby a thin layer of mercury distributed over said surface is produced. After the anode has been thoroughly amalgamated the side tube 6 may or may not be sealed off from the envelope, as desired. By first utilizing a quantity of distilled mercury contained in the capsule and then later re-distilling the material into the envelope, a double distillation process, a very pure conditions of the mercury surface is assured. It is to be noted that the second distillation step is deliberately provided for by forming the tube 6 with an approximate right-angle bend which together with trap member 7 precludes accidental movement of the liquid into the main envelope by gravity in which case the amalgamation would be only partially complete and the liquid if in excess, would en-

dow the device with those undesirable characteristics which have been pointed out hereinbefore. However, it is to be understood that the omission of the second distillation step is within the contemplation of our invention provided there is present an amalgamated surface having area large enough to provide sufficient vapor for effectively reducing space-charge.

On test, a rectifier such as described, consistently shows a constant operating characteristic and there is sufficient amalgam present to furnish vapor for a long tube operating life. It is evident that the liquid mercury in the reservoir 7 is always available to renew the amalgam, if desired, although we have found that further distillation is not necessary even after long continued operation, hence, the side tube 6 normally is sealed-off. The vapor may be formed readily within the device upon application of suitable voltage because the amalgamated surface upon which the heat and electrostatic field act is large, hence, the tube attains its normal operating characteristics almost immediately. If desired, the anode temperature may be controlled independently of the tube operation, for example, by heating or cooling the circulatory fluid so that the proper vapor pressure is available at the same instant that the operating potential is applied. It is found that the vapor pressure remains at a desirable value, accurately controllable, by regulating the anode temperature in the manner stated. The desirable anode temperature may vary over a considerable range depending upon the manner in which the device is operated; in one type of rectifier with 20,000 volts applied between the cathode and anode and an output of approximately 45 k. w., the most efficient operating temperature has been found to be in the neighborhood of 60° C. A device such as described lends itself particularly well to all forms of electron discharge devices, i. e., those in which the current is carried principally by electrons and which employ a plurality of elements including an electron emitting source and a substance in the form of vapor to reduce space charge or to offset other deleterious action. It has special adaptation to high-voltage, high-powered electric discharge apparatus, for example rectifiers, also to devices of the thyratron type so-called which utilize an electrostatic control member for controlling a discharge of arc-like character as described and claimed in application Serial No. 268,975, filed April 10, 1928, in the name of A. W. Hull and assigned to the same assignee as the present application.

While we have described our invention with particular reference to mercury as the condensate or the vapor-producing component of the alloy, it is evident that other materials may be employed to advantage, for

example, suitable alkali metals such as caesium and rubidium, the vapor pressure of which is sufficiently high at operating temperatures and which are capable of forming a condensate or alloy. It is also feasible to employ iodine for the purposes stated which may be applied to the interior surface of the anode by painting or in any other suitable manner. The present invention therefore contemplates the use of any substance, liquid and solid, which, at readily attainable temperatures, supplies vapor in quantity sufficient to eradicate space charge and which is capable of adhering to a member in the device to form a vapor-yielding surface, said member responding quickly and accurately to temperature control. It is obviously necessary to choose the metal of the anode or of other member upon which the active surface is formed with the specific vapor-producing material in mind so that an effective surface be produced. In the event that materials are employed which will give the desired vapor pressure only at temperatures in excess of the temperature which glass portion 2 normally attains during operation, it may be necessary to maintain this portion of the container at a temperature higher than the said temperatures, for example, by means of a heat-absorbing enclosure (not shown) in order to ensure that the condensation of the vapor-producing substance takes place at a position in the device, e. g., at the water-jacketed end, where there is provided facility of accurately controlling the temperature of the condensate. In the case of mercury however, the glass portion is normally at a sufficiently elevated temperature under operating conditions even when exposed directly to the air, substantially to exclude the mercury from collecting in the upper portion of the container. For this and other reasons we consider mercury to be a preferable material from which to derive the space-charge-reducing vapor.

From the foregoing, it is evident that the invention is not limited to rectifiers or two-electrode devices such as has been shown for the sake of illustrating the principles involved, but may be applied to all forms of electrical discharge apparatus, amplifiers, oscillators and the like wherein space current is carried in the absence of cumulative or substantial ionization. Accordingly, we desire no restriction placed upon the scope of the invention as set forth in the following claims except as may be demanded by the prior art.

What we claim as new and desire to secure by Letters Patent of the United States, is:

1. A thermionic device comprising a filamentary cathode and a cooperating anode between which the discharge tends to be limited by space charge, said anode being

adapted to have its temperature controlled, and means, comprising a substance forming a substantial coating on said anode, for reducing space charge.

2. A thermionic device comprising an evacuated envelope containing an electron emitting cathode and a cooperating anode in heat-receiving relation therewith whose temperature is adapted to be varied, means for reducing the space-charge which limits the current flow between the electrodes, said means comprising a vapor-generating substance spread over the surface of said anode whereby the rate of generation of the vapor may be regulated to maintain a substantially constant space-charge-reducing effect.

3. A thermionic device comprising a plurality of electrodes between which the discharge tends to be limited by space-charge, means for varying the operating temperature of one of said electrodes and means for minimizing the space-charge, said last mentioned means comprising a condensable vapor, the pressure of which is maintained at a predetermined value by the temperature of the electrode adapted to be varied.

4. A thermionic device comprising a plurality of electrodes between which the discharge tends to be limited by space-charge effect, means for substantially neutralizing the space charge, said means comprising a coat of space-charge-reducing material on one of said electrodes, and means for vaporizing and maintaining substantially constant the vapor pressure of said material, said last mentioned means including a device for varying the temperature of the said one electrode.

5. In the art of operating a thermionic device comprising an evacuated envelope, cooperating electrodes therein including a source of electrons, one of said electrodes being amalgamated, the method which consists in varying the temperature of the electrode to maintain a sufficient quantity of mercury vapor in the device to reduce space charge effect.

6. A thermionic device comprising an electrode having an amalgamated surface, the temperature of which is adapted to be varied within a temperature range including the temperature necessary to produce a mercury vapor in quantity sufficient for reducing space charge to a desired extent and means for maintaining said surface at such vapor-producing temperature.

7. A thermionic device comprising a plurality of electrodes between which the discharge tends to be limited by space-charge, means for substantially neutralizing the space charge, said means including a temperature-varying device and a layer on one of said electrodes of a vapor-producing substance in the absence of any of said substance in loose form.

8. A thermionic device comprising an

anode having an amalgamated surface in the absence of an excess of liquid mercury, the temperature of said anode being adapted to be varied whereby mercury vapor is evolved from the anode surface and its pressure maintained at a desired value.

9. A thermionic device comprising an envelope containing an electron emitting cathode and a cooperating anode with an amalgamated surface, the temperature of which is adapted to be varied whereby mercury vapor is evolved from the anode surface and its pressure maintained at a desired value.

10. A thermionic device comprising an electron emitting cathode and a cooperating anode between which space current is carried principally by electrons, means for reducing space charge, said means comprising a source of vapor distributed over a surface in the device, the temperature of said surface being adapted to be varied, said means comprising an amalgam on the anode.

11. A thermionic device comprising the combination of an evacuated envelope containing a cathode adapted to emit electrons and cooperating electrodes between which current is carried principally by electrons, a source of ion-producing vapor associated with said envelope for reducing space charge, the material of one of said electrodes other than the cathode being such as to allow the formation of a condensate derived from said vapor under operating conditions, said electrode being adapted to have its temperature varied.

12. A thermionic device comprising the combination of an evacuated envelope having an exterior portion formed of a metal comprising copper and constituting an electrode, said envelope containing a cathode adapted to emit and to propagate electrons toward said electrode, a source of mercury-yielding material associated with said envelope and forming with the copper, an amalgamated surface.

13. A thermionic device comprising an envelope containing an electron emitting cathode and a cooperating element provided with an amalgamated surface, temperature-varying means for causing the alternate release of the mercury from said surface and the condensation of the released mercury on the surface.

14. A thermionic device comprising an envelope containing an electron emitting cathode and a cooperating element provided with an amalgamated surface, means for varying the temperature of said surface whereby the mercury is alternately evolved and condensed on said surface.

15. A thermionic device comprising an envelope containing an electron emitting cathode and a cooperating element provided with an amalgamated surface, temperature-varying means for releasing the mercury from

said surface and for maintaining the pressure of said vapor at a desired value.

In witness whereof, MARCUS A. ACHESON has hereunto set his hand this 23rd day of August, 1928, and JAMES L. ZEHNER has hereunto set his hand this 29th day of August, 1928.
